EXPANSION CHAMBER FOR PRESSURE
CORE BARRELS

Benjamin W. Sewell, Tulsa, Okla., assignor to
Standard Oil Development Company, a cor-
poration of Delaware

Application February 10, 1940, Serial No. 318,266

6 Claims. (Cl. 255—72)

The present invention relates to expansion members for pressure core barrels.

It is an object of the present invention to provide a pressure core barrel with means for reducing the differential pressure in the barrel when it is withdrawn to the surface of the earth.

It is a further object of the present invention to provide a pressure core barrel with expandable means which will allow the pressure chamber to increase in volume as the core barrel is withdrawn to the surface of the earth and thereby reduce the pressure differential within the core barrel.

Another object of the present invention is to provide a core barrel with means which will retain the fluid in the barrel and yet allow the pressure in the barrel to be substantially reduced below the pressure of the formation from which the core is obtained.

Other objects and advantages of the present invention may be seen from reading the following description and by reference to the accompanying drawings in which:

Fig. 1 is a cross sectional view of a portion of a pressure core barrel showing one modification of the present invention applied thereto;

Fig. 2 is a cross sectional view of a portion of a core barrel similar to that shown in Fig. 1 having applied thereto another modification of the present invention;

Fig. 3 is a cross sectional view of a portion of a core barrel showing applied thereto another modification of the present invention, while

Fig. 4 shows the same portion of a core barrel illustrated in Fig. 3 having applied thereto still another modification of the present invention.

While the present invention may be applied generally to pressure core barrels, it is shown in the present application as applied to the pressure core barrel described in my Patent 2,238,609 of April 15, 1941 to facilitate the description thereof, parts are designated by the same numerals as are applied to like parts in the above mentioned copending application. The complete pressure core barrel described in said patent has not been shown in the present application because the means herein described are applicable to pressure core barrels in general and are not dependent on the mechanism used in any particular core barrel. The operation of the present invention and its relationship to pressure core barrels will be clearly understood from the following description of the accompanying drawings.

Referring specifically to the drawings and first

5 to Fig. 1, numeral 5 is a cylinder which forms a portion of a drill stem. Concentrically inside of cylinder 5 is cylinder 35 which is provided at its upper end with a cylindrical block 36 provided with a central passage 37. Central passage 37 is 10 enlarged at its lower end to provide annular space 38. At the lower end of annular space 38 is downwardly extending knife edge 53. A radial passage 39 connects space 38 with the exterior of 15 the block. The block is also provided with a laterally offset longitudinal passage 40, controlled by a needle valve 41 and, when open, making connection with a lateral passage 42 provided with a plug 43 for the purpose hereinafter specified. Block 36 is provided radially extending longitudinal fins 64 which space it from cylinder 5.

20 Positioned concentrically inside of cylinder 35 is another cylinder, not shown, which acts to receive a core. This core receiving cylinder is connected to collar 51 which, in turn, is connected to the lower end of rod 25. As may be seen in the drawings, rod 25 extends upwardly through central passage 37 and is connected at its upper end 25 with a coupling 24 which, in turn, is connected to a rod 20. Collar 51 is provided with a laterally extending upper face upon which is arranged a strip of resilient material 52 of such dimensions 30 as to form seat for the knife edge 53 for reasons which will be hereinafter explained.

35 Extending upwardly from block 36 is a sleeve 44 concentric with coupling 24, said sleeve normally having a smaller inner diameter than the outside diameter of coupling 24, but being reamed out to form a sliding fit for said coupling for a length defined by shoulders 45 and 46, whereby 40 said coupling is permitted limited longitudinal movement within said sleeve for the purpose hereinafter specified.

45 At its upper end sleeve 44 is provided with radially extending longitudinally arranged fins 47 which have inclined upper edges 48 adapted to form a seat for the bevelled edge 49 of the inside edge of the lower end of a cylindrical section 7. Section 7 is also provided adjacent its lower end with an external shoulder 50. There is a linkage 45 between section 7 and the upper end of rod 20 which is not shown in the drawings.

50 In this figure an expandable means is provided by a rubber sleeve 101 which embraces metal cylinder 35. Clamps 102 form a fluid-tight joint between sleeve 101 and cylinder 35 at the ends of the rubber sleeve. Perforations 103 in the wall of cylinder 35 provide a fluid connection

between the interior of sleeve 35 and expandable member 101.

In operating the core barrel it is lowered into the hole until the core bit, not shown, strikes the formation at the bottom of the hole as is conventional in the art. When the inner core barrel strikes the bottom of the hole, it forces rod 25 upwardly which, in turn, communicates the thrust through collar 24 and rod 20 so that locking means, not shown, firmly locks rod 20 with sleeve 7. The device is then rotated to cut a core in the manner conventional to the art and as the solid core enters the cylinder 35 it displaces drilling fluid through passage 38. After a suitable core has been cut, an upward pull is communicated from sleeve 7 through the locking means, not shown, to rod 20 which, in turn, communicates the pull through collar 24, rod 25 and collar 51 to the inner core barrel (not shown). This upward pull withdraws the inner core barrel within cylinder 35 and allows a valve (not shown) at the lower end of cylinder 35 to close. A continued pull draws collar 51 provided with seat 52 against knife edge 53 effectively closing the upper portion of cylinder 35. With cylinder 35 sealed off at the upper and lower end the core barrel containing the core may be withdrawn to the surface of the earth.

It will be appreciated that, when the core is obtained, it is sealed in a fluid-tight manner under the pressure of the formation from which it is obtained and that ordinarily, as the core barrel is withdrawn to the surface of the earth, the pressure differential becomes successively greater because the pressure on the exterior of the cylinder holding the core becomes less and less, while the pressure within it remains constant. However, in the present case cylinder 35 is provided with expandable sleeve 101 which allows the gases within the pressure core barrel to expand. At the formation pressure the gases in the core occupy only a small part of the total volume occupied by the core, so the volume required for gas expansion in order to greatly reduce the pressure within the barrel need not be large. It will be understood that the volume required for expansion may be several times larger than the volume required to contain the core itself, but that this volume is not large compared with the great pressure reduction obtained. For example, it is preferred to keep the differential pressure within the core barrel at from fifty to one hundred pounds per square inch when the device is withdrawn to the surface of the earth, and at times the formation pressure under which the core is sealed within the barrel may be as great as four thousand pounds per square inch. It will be understood that the drawing is not shown to scale and that any length of rubber sleeve desired may be provided for cylinder 35 in order to allow the proper pressure reduction.

In Fig. 2 the same type of core barrel as shown in Fig. 1 is illustrated. However, in the modification of the pressure reduction means shown in this figure the cylindrical head 36 is provided with a longitudinal passage 104. A Sylphon bellows 105 is provided on the upper face of cylindrical block 36 to control the upper end of passage 104. It will be noted that in Fig. 2 the 70 space between the upper face of block 36 and

the lower portion of arm 47 is of such dimensions as to provide room for the expandable member 105. It will be understood that in withdrawing the device from the bore hole shoulder 5 47 moves upwardly with respect to the upper face of block 36, seals the upper end of cylinder 35 and, in so doing, increases the space in which the Sylphon bellows 105 may expand in order to reduce the pressure within cylinder 35.

Fig. 3 is a view of the portion of the core barrels illustrated in the preceding figures provided with an expandable member 106 in the form of a rubber balloon. This device is operated in the same general manner as the Sylphon bellows shown in Fig. 2, the only difference being that a balloon is used as the expandable member instead of the Sylphon bellows.

In Fig. 4, a modification of the invention is shown in which the expansion member is telescoping member 107. The device shown in this figure operates in the same manner as that shown in Figs. 2 and 3.

While I have shown the modification of the present invention as applied to the core barrel described in my copending application Serial No. 269,168, it will be apparent that these modifications may be applied to the pressure core barrels shown in copending Patents Nos. 2,213,595 of Sept. 3, 1940, and 2,216,962 of Oct. 8, 1940, and copending application No. 310,284 filed Dec. 21, 1939. The modifications of the present invention may be applied not only to any of the above mentioned core barrels, but also to other pressure core barrels to which an expandable member may be attached to allow the pressure within the core barrel to be reduced as the core barrel is withdrawn from the bore hole to the surface of the earth.

Having fully described and illustrated the present invention, what I desire to claim is:

1. In a pressure core barrel provided with a pressure chamber adapted to be closed in a fluid-tight manner, a fluid-tight expandable member fluidly connected to the pressure chamber.

2. A pressure core barrel comprising a cylindrical chamber adapted to be closed in a fluid-tight manner and having attached thereto a fluid-tight expandable member in fluid communication with the interior of said chamber.

3. A pressure core barrel comprising a cylindrical chamber adapted to receive a core and to be sealed in a fluid-tight manner and having arranged adjacent its exterior an expandable fluid-tight means in fluid communication with the interior of the chamber.

4. An apparatus in accordance with claim 3 in which the expandable member comprises a rubber sleeve circumferentially embracing the cylindrical member and provided with clamps firmly attaching its ends to said cylindrical member.

5. An apparatus in accordance with claim 3 in which a chamber having expandable walls is attached to the upper end of the core barrel and communicates with the interior of the core barrel by a passage through its upper end.

6. An apparatus in accordance with claim 3 in which the expandable member is a telescoping device arranged in the upper end of said core barrel.

BENJAMIN W. SEWELL.
